United States Patent

Des. 235,317
Patented June 10, 1975

235,317

STUD FINDER

Laird F. Covey, Easton, Conn., assignor to The Stanley Works, New Britain, Conn.

Filed Feb. 26, 1973, Ser. No. 335,650

Term of patent 14 years

Int. Cl. D10—05

U.S. Cl. D10—46

FIG. 1

FIG. 2

FIG. 3

FIG. 4

FIG. 5

FIG. 6

FIG. 1 is a perspective view of a stud finder embodying my new design;

FIG. 2 is a side elevational view thereof, the opposite side being a mirror image thereof;

FIG. 3 is a plan view thereof;

FIG. 4 is a bottom view thereof;

FIG. 5 is an end elevational view thereof; and

FIG. 6 is an elevational view of the end opposite that shown in FIG. 5.

I claim:

An ornamental design for a stud finder, as shown.
